ABSTRACT OF THE DISCLOSURE

This application discloses a sheet metal clip having a shank portion adapted to be snapped into an aperture of an electrically nonconductive supporting panel, said shank including fingers which are laterally yieldable to permit insertion of the shank in a work aperture to spring outwardly automatically upon complete insertion, and thus secure the shank against unauthorized removal from the panel, the portion of the clip oppositely disposed from the shank having means for detachably receiving the free extremity of an electrical conductor.

Specification

It is an important object of the present invention to provide a terminal clip of improved practical construction which may be telescopically associated with an apertured panel and secured on one side thereof, and which is adapted after such association to accommodate the free extremities of electrical conductors positioned on the opposite side of the panel.

More specifically, the invention contemplates a novel shank portion for accommodating the free extremities of electrical conductors on one side of a panel, and novel structural means for detachably accommodating the free extremity of an electrical conductor located on the opposite side of the panel.

The foregoing and other objects and advantages will be more apparent from the following detailed description, when considered in connection with the accompanying drawings, wherein:

FIG. 1 is a perspective view of a clip or terminal which is representative of one embodiment of the invention;

FIG. 2 is a perspective view of the upper portion of the clip as disclosed in FIG. 1, associated with a fragmentary portion of a supporting panel, an electrical conductor being shown in operative and detachable association with the clip;

FIG. 3 is a vertical sectional view taken substantially along the line 3—3 of FIG. 2, the dot-and-dash lines indicating the position of the shiftable clip arm or plate before it has been depressed to the solid line position;

FIG. 4 is a fragmentary side elevation of the clip of FIG. 1, as viewed from the line 4—4 of FIG. 1 after the clip has been telescopically associated with the panel member;

FIG. 5 is a fragmentary perspective view of a modified form of clip, the upper portion of the clip having means for receiving a terminal screw member;

FIG. 6 is a sectional view taken substantially along the line 6—6 of FIG. 5;

FIGS. 7 to 16, inclusive, disclose a further modified form of clip equipped with a nonconductive sheath for supporting and insulating an elongated terminal member;

FIG. 7 being a side elevation of this modified clip disclosing the flexible arm of the clip in contact with the elongated terminal element associated with said sheath;

FIG. 8 is an elevational view taken from the right of FIG. 7;

FIG. 9 is a view of the upper portion of FIG. 7, disclosing the shiftable arm of the clip in its lower position out of contact with the elongated terminal element;

FIG. 10 is a plan view of the device as shown in FIG. 9;

FIG. 11 is a central sectional view taken substantially along the line 11—11 of FIG. 10;

FIG. 12 is also a sectional view taken substantially along the line 12—12 of FIG. 11;

FIG. 13 is a horizontal sectional view taken substantially along the line 13—13 of FIG. 11;

FIG. 14 is a fragmentary perspective view of the electrically nonconductive support for the elongated terminal member of the clip;

FIG. 15 is a plan view of the device as shown in FIG. 14 prior to bending the terminal support to the position shown in FIG. 13; and

FIG. 16 is a fragmentary front elevational view of the terminal support as shown in FIG. 15.

Referring now to the drawings, wherein like numerals have been employed to designate similar parts throughout the various views, it will be seen that one embodiment of a clip conforming to the present invention is disclosed in FIGS. 1—4 inclusive. The clip in these figures is designated generally by the numeral 18, the lower or shank portion thereof being designated by the numeral 20, while the upper portion or section of the clip is designated generally by the numeral 22. The upper portion 22 is adapted to detachably accommodate the extremity of a conductor element 24 while the lower or shank portion 20 is designed for insertion within an aperture 26 of a panel 28.

The shank portion 20 consists of two shank elements 30 and 32 depending from and formed integral with opposed margins of a plate or body portion 34. A locking finger 36, struck from the shank element 30, and a corresponding locking finger 38, struck from the shank element 32, are normally inclined outwardly from the plane of their respective shank elements. The free extremity of the finger 36 is bent to provide a panel engaging tongue 40 and the free extremity of the finger or arm 38 is likewise formed with a panel engaging tongue 42. These tongues 40 and 42 are spaced equally from the plane of the plate or body 34 and are adapted to interlock with margins of the panel 28 defining the aperture 26, as illustrated in FIG. 4. It will also be noted that these tongues 40 and 42 are positioned diagonally opposite each other.

The shank element 30 is also provided with a struck-out finger 44, and the shank element 32 is provided with a corresponding diagonally positioned finger 46. The finger 44 provides a deflected portion 48 and the finger 46, at its free extremity, presents a similar tongue 50. The tongues 48 and 50 are equally spaced from the plane of the body plate 45, but at a greater distance than the tongues 40 and 42, for purposes about to be explained.

From the foregoing, it will be apparent that the shank portion 20 of the clip 18 is adapted to be telescopically associated with the panel aperture 26 and when fully inserted will be secured in such position by the cooperation of the tongues 40 and 42, as clearly illustrated in FIG. 4. If the work panel is thicker than the panel 28, disclosed in the drawing, the tongues 48 and 50 may then be brought into play for locking the clip into position.

The portion 22 of the clip 18 which is designed to accommodate the conductor member 24, includes a laterally shiftable arm 52 which is integrally and hingedly connected at 54 with one margin of the plate body 34. One of the side margins of the plate 22 is provided with an extension 56, the intermediate portion 58 being struck outwardly as shown in FIGS. 1—4, inclusive. A section

60 of the arm 52 is bent oppositely with respect to the section 58 so as to provide an aperture 62 for accommodating the free extremity of the conductor 24. A section 64 of the arm 52 is bent laterally in a manner similar to the section 60, and these sections are separated by a recess 66. It will be noted that the central portion of the body or plate 34 is struck out so as to provide a hook 68 which is in registration with the recess 66. This hook is so positioned that as the arm 52 is shifted from the position shown in FIG. 1 to the position shown in FIGS. 2 and 3, the area defined by the free extremity of the hook is brought into alignment with the aperture 62, and in this position the conductor 24 may be telescopically associated with the clip as shown in FIG. 2. In this position good electrical contact is established between the conductor 24 and the clip 18.

It is common practice for the free extremity of an antenna conductor to be formed with a right-angular bend, such as incorporated in the conductor 24. In such instances the presence of the extension 56 serves as a stop or abutment to limit the extent of axial insertion of the free extremity of the conductor. It is important to prevent this extremity of a conductor from projecting beyond the margin or edge of the arm. Clips of the type just described are commonly mounted in adjacent relationship along a panel, and therefore should the extremity of the conductor 24 project an appreciable amount beyond the margin of the arm 52, there is a potential hazard of contacting the next adjacent clip and thus causing a short circuit.

In FIGS. 5 and 6 a modified form of clip is shown which is designated generally by the numeral 18a. A shank portion 20a of the clip 18a is structurally similar to the shank portion 20 previously described. The upper portion of the clip 18a does not incorporate the shiftable arm 52 as shown in FIGS. 1-4 inclusive, but is provided with a screw accommodating helix 70 struck from the plate or body portion 34a. A terminal screw member 72 is employed to secure electrical contact of a conductor 24a with the clip 18a. Other structural features of the shank 20a are designated by numerals bearing the suffix *a* corresponding with the numerals employed in FIGS. 1-4, inclusive.

In FIGS. 7-13, inclusive, a further modification of the clip is shown. In many respects the clip disclosed in FIGS. 7-13 inclusive, designated generally by the numeral 18b, is similar structurally to the clip 18 previously described. Parts of the clip 18b corresponding with parts of the clip 18 are designated by similar numbers, bearing the suffix *b*. The similarity of these corresponding parts will be quite apparent from the drawings. An important distinguishing feature of the clip 18b is the use of an elongated electrical terminal or connector element 74. The upper extremity of the terminal member 74 extends laterally from an elongated portion, as indicated in FIGS. 7, 9, and 11, and is designed to make electrical contact with the arm 52b of the clip member 18b when said arm occupies the position illustrated in FIGS. 7 and 11. The terminal member 74 is insulated from the other portions of the clip 18b, and is supported in position by a member 76, made of suitable nonconductive, preferably bendable, material such as a suitable plastic. It will be noted that this member 76 includes a pair of sheath sections 78 adapted to accommodate the upper portion of the conductor 74 when the parts 78 are brought into juxtaposition with the recesses 80 of the sections 78 in registration with each other. The member 76 initially assumes the shape shown in FIGS. 14-16, inclusive.

An area 82 of reduced cross-section facilitates bending 70 at this point, enabling each half of the member 76 to be brought into registering engagement with the other companion half. A protuberance 84, when brought into telescopic association with a complementary aperture 86, assures proper alignment of the recesses 80. Before the 75

part 76 is completely folded together, the conductor 74 may be assembled within one of the companion recesses 80.

Extending beyond each of the sheath sections 78 is a laterally flexible finger or latch member 88. When the member 76 has been folded so as to completely enclose the upper portion of the connector 74, the member 76 may be inserted within the recess 66b, thereby bringing the fingers 88 into interlocking or latching engagement with the hook member 68b, as clearly illustrated in FIG. 13. The member 76 is thus securely held within and electrically insulated from the clip 18b when the arm 52b occupies the position shown in FIG. 9. In this position an electrical conductor such as the conductor 24 previously referred to may be connected with a circuit such as an antenna circuit positioned externally of the panel. On the other hand, if an internal antenna circuit is to be employed, it is only necessary to remove the conductor 24, thereby enabling the arm 52b to be biased into contact with the upper extremity of the terminal member 74. The clip may now be electrically coupled with an internal antenna circuit through a conductor 90 connected with the free extremity of the terminal member 74. This is representative of only one of the many practical applications 25 of the clip contemplated by the present invention.

From the foregoing it will be apparent that the present invention contemplates a sheet metal clip of novel and practical form. The combination of the novel snap-in shank portion with the novel arrangement for detachably 30 accommodating a conductor extremity makes it possible to mount a series of clips within adjacently positioned panel apertures without any danger of short circuits, and with the assurance that the clip will be securely held in proper position upon the panel. By incorporating the 35 elongated terminal member which may be selectively insulated from or electrically connected with the sheet metal clip, the ease with which antennas or other electrical devices may be selectively coupled with external or internal circuits, is greatly facilitated.

While for purposes of illustration certain structural features have been disclosed herein, it should be understood that the present invention contemplates other modifications and changes and should be limited only by the scope of the appended claims.

The invention is claimed as follows:

1. In a generally U-shaped electric wire connector terminal clip formed of a single piece of relatively thin spring sheet metal, adapted to be operatively secured to a relatively thin and generally form-retaining insulating work panel by having its two legs inserted into a mounting hole in such panel, such clip having a central body portion constituting the base of the U and having two generally parallel juxtaposed hole-entering shank elements bent downwardly from said body portion along generally parallel spaced apart boundaries thereof coincident with the bend lines and constituting the two legs of the U and having opposite external extensions extending laterally from opposite edges of said body portion which are intermediate the aforementioned bend line edges of said central body portion, the improvements which include a generally elongated spring finger struck in its entirety from each of said legs along a longitudinal edge thereof, with said spring fingers being resiliently connected with said legs at the ends of the spring fingers farthest from said body portions, each of said spring fingers in its unsprung condition diverging outwardly from its connection with said leg for a substantial portion of its length and then bent inwardly toward said leg to form a tongue having an inclined upper panel engaging surface facing generally in the direction of the aforementioned body portion of the clip, and means associated with said connector for detachably accommodating an electrical conductor.

2. A one-piece sheet metal electrical clip as set forth in claim 1, wherein said plate-like member is substantially polygonal in shape and wherein one of said yieldable

spring fingers is positioned in the vicinity of each corner of said body member.

3. A one piece sheet metal electrical clip as set forth in claim 2, wherein the free extremity of a pair of diagonally positioned spring fingers is spaced a greater distance from the plane of the body than the free extremities of a remaining pair of spring fingers whereby the inclined tongues on one pair of fingers will accept panels having a given range of tolerances and the second pair of fingers will accept panels of an even greater thickness range.

4. A one-piece sheet metal electrical clip as set forth in claim 1, wherein the means for detachably accommodating an electrical conductor includes a yieldable contact arm inclined to and hingedly connected with a margin of said body member, conductor accommodating hook means struck from within the margins of said body and with the closed end of said hook extending upwardly toward said contact arm, a portion of said contact arm being recessed for telescopically accommodating said hook means when said arm is depressed toward said body, sections of said arm on opposite sides of said recess being bent downwardly toward said body and a marginal extension on said contact arm being bent in the opposite direction from said sections, said extension and said hook being adapted to form a conductor receiving opening in cooperation with said bent down sections when said arm is depressed to form a four point support for said conductor, said marginal extension adapted to serve as limiting abutment when a bent conductor is inserted into said opening.

5. A sheet metal electrical clip including a plate-like body member, shank means for insertion within an aperture of a supporting workpiece such as a panel member, said shank means including yieldable work engaging members movable in one direction to permit telescopic association of said shank means within a work aperture and biased to spring laterally in the opposite direction into work-interlocking position upon the complete insertion thereof, means associated with said plate-like member for detachably accommodating an electrical conductor, and an elongated electrical terminal supported on the clip and extending substantially normal to and traversing said plate-like body, an exposed extremity of said terminal member positioned on one side of said body and an opposite exposed extremity thereof positioned on the other side of said body.

6. A sheet metal electrical clip as set forth in claim 5, including means comprised of electrically insulating material associated with said plate-like body for supporting said elongated terminal member.

5 7. A sheet metal electrical clip as set forth in claim 5, wherein the means for detachably accommodating an electrical conductor includes a laterally yieldable contact arm which is selectively engageable with an exposed extremity of the terminal member positioned on one side of the plate-like body member.

10 8. A sheet metal electrical clip as set forth in claim 5, wherein the means for detachably accommodating an electrical conductor includes a laterally yieldable contact arm hingedly connected with said body member, said contact arm and body member being recessed to accommodate said elongated electrical terminal.

15 9. A sheet metal electrical clip as set forth in claim 5, wherein one exposed extremity of said terminal member extends laterally of the remaining portion of said terminal member, and wherein said means for detachably accommodating an electrical conductor includes a laterally yieldable contact arm adapted selectively to contact the laterally extending portion of said elongated terminal member.

20 10. A sheet metal electrical clip as set forth in claim 9, including means comprised of electrically insulating material for supporting said elongated terminal member on said plate-like body.
